Primary Examiner — Karen S Acker

Assistant Examiner — Steven B Reinholdt, Jr.

(74) Attorney, Agent, or Firm — Merchant & Gould P.C.

(57) **CLAIM**

The ornamental design for an insect trap, as shown and described.

DESCRIPTION

FIG. 1 is a top, left, front perspective view of a first embodiment of an insect trap according to the new design; FIG. 2 is a front view of the insect trap of FIG. 1; FIG. 3 is a back view of the insect trap of FIG. 1; FIG. 4 is a right side view of the insect trap of FIG. 1; FIG. 5 is a left side view of the insect trap of FIG. 1; FIG. 6 is a top view of the insect trap of FIG. 1; FIG. 7 is a bottom view of the insect trap of FIG. 1; FIG. 8 is a top, left, front perspective view of a second embodiment of an insect trap according to the new design; FIG. 9 is a front view of the insect trap of FIG. 8; FIG. 10 is a back side view of the insect trap of FIG. 8; FIG. 11 is a right side view of the insect trap of FIG. 8; FIG. 12 is a left view of the insect trap of FIG. 8; FIG. 13 is a top view of the insect trap of FIG. 8; FIG. 14 is a bottom view of the insect trap of FIG. 8; FIG. 15 is a top, left, front perspective view of a third embodiment of an insect trap according to the new design; FIG. 16 is a front view of the insect trap of FIG. 15; FIG. 17 is a back view of the insect trap of FIG. 15; FIG. 18 is a right side view of the insect trap of FIG. 15; FIG. 19 is a left side view of the insect trap of FIG. 15; FIG. 20 is a top view of the insect trap of FIG. 15; and, FIG. 21 is a bottom view of the insect trap of FIG. 15. In the above drawings, the broken lines and the areas within the broken lines form no part of the claimed design.

1 Claim, 21 Drawing Sheets
